UNITED STATES PATENT OFFICE

128,164

DESIGN FOR A COMBINED BURNER BOWL AND UTENSIL SUPPORT FOR RANGES

John F. Hennessy, Rockford, Ill., assignor to Geo.
D. Roper Corporation, Rockford, Ill., a corpora-
tion of Illinois

Application December 7, 1939, Serial No. 88,749

Term of patent 7 years

To all whom it may concern:

Be it known that I, John F. Hennessy, a citizen of the United States, residing at Rockford, in the county of Winnebago and State of Illinois, have invented a new, original, and ornamental Design for a Combined Burner Bowl and Utensil Support for Ranges, of which the following is a specification, reference being had to the accompanying drawing, forming part thereof.

In the drawing:

Fig. 1 is a perspective view of a combined burner bowl and utensil support for ranges showing my new design;

Fig. 2 is a top plan view thereof, and
Fig. 3 is a sectional detail of the bowl taken on
the line 3—3 of Fig. 2, the utensil support being
removed.

The underside of the bowl is substantially plain.

I claim:

The ornamental design for a combined burner
bowl and utensil support for ranges, substantially
as shown and described.

JOHN F. HENNESSY.
